UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

OPERATING MECHANISM FOR CAR-DOORS.

1,221,202.

Specification of Letters Patent.

Patented Apr. 3, 1917.

Application filed March 11, 1913. Serial No. 753,636.

To all whom it may concern:

Be it known that I, JAMES F. McELROY, a citizen of the United States, residing at Albany, county of Albany, State of New York, have invented certain new and useful Improvements in Operating Mechanism for Car-Doors, the following being a full, clear, and exact disclosure of the one form of my invention which I at present deem preferable.

For a detailed description of the present form of my invention, reference may be had to the following specification and to the accompanying drawing, which illustrates my invention, wherein—

Figure 1 is a general view of my apparatus;

Fig. 2 is a plan thereof;

Fig. 3 shows the vertical shaft and handles;

Figs. 4 and 5 show details.

My invention relates to the operation of doors, particularly car doors. It is shown as applied to a door formed in sections hinged to each other and one section hinged to the door frame. The outer or wing section is provided with a roller at its outer corner which travels in a straight guide extending along the line occupied by the door when it is closed. I have devised a simple system of levers for operating such a door from a point or station which is more or less distant from the door. I thus avoid the use of gear wheels and bearings therefor.

Turning to the accompanying drawings, A, A¹ represent the two sections of a car door and B, B¹ represent the corresponding sections of a second door beside the first one and separated therefrom by the post C. Both of these doors are to be operated from the same point on the car platform adjacent to the rail E, by means of the respective handles A¹² and B¹². As appears in Fig. 3, the handle A¹² serves to rotate a vertical shaft A¹¹ mounted on rail E and the handle B¹² a tubular shaft B¹¹ which surrounds A¹¹. Braces F¹ and F² serve to stay the upper ends of the said shafts and the two handles may be locked, if desired, by a pin E¹ that is dropped loosely in a socket on the rail E.

The operating devices for one door are duplicated for the other and hence I will only describe those for door A A¹. This door has on the upper outer corner of its

wing section A a roller a which travels between straight horizontal guide strips a¹ which lie just above the line of the door when it is closed. The meeting edges of the door sections swing outward to open, the outer edge of the wing section moving in a straight line toward the hinged edge of the main section until they meet. In Fig. 2 the closed position of door A¹ is shown in full lines, its open position in dotted lines; whereas for door B, B¹ the full lines show the open and the dotted lines the closed position of that door. To the middle point of wing section A near its upper edge is jointed one end of a light bar A³, the opposite end of which is hinged to one end of a shorter bar A² which has its other end hinged to the door frame and forms a shifting fulcrum for the bar A³. When the door is closed, these bars A², A³ stand at an angle to the door and to each other, as shown in Fig. 2. To the center of bar A³ is hinged the connecting rod A⁸ which is jointed at its opposite end to the crank arm A¹⁰ by means of an offset A¹⁵, so as to bring the joint between A¹⁰ and A¹⁵ back of the vertical shaft A¹¹ when the door is closed, as appears in said Fig. 2. This arrangement serves to lock the doors by throwing the crank A¹⁰ to or slightly beyond dead center when the connecting rod A⁸ comes against the side of the vertical shaft. It similarly locks the doors in their open position. When door A is closed, as in Fig. 2, a clockwise rotation of shaft A¹¹ by handle A¹² will cause the rod A⁸ to push against the bar A³, thereby breaking the toggle joint between the two door sections, pushing the section A at the same time bodily inward toward the door frame and causing its outer edge, which is controlled by the roller a in guides a¹, to move toward the inner or hinged edge of section A¹ until both sections are folded together and project outward at right angles to their closed position, as is shown by the dotted lines at the right. The right hand end of bar A³ follows an arc traced by the outer end of bar A² acting as a radius and finally comes into a position parallel to the folded and opened doors as shown by the dotted lines in the figure. To close the door a reverse movement is given to handle A¹² causing the rod A⁸ to draw inward on the bar A³, and since that bar is jointed to the wing section of

the door it will pull that section directly forward without any binding effect until that section, followed by section A¹, comes into its closed position. At no point in the 5 range of movement of the door sections is there any force exerted in a line across a dead center or approximating thereto such as is the common cause of the binding and sticking of doors of this type.

10. What I claim as new and desire to secure by Letters Patent is:

1. An operating mechanism for sectional doors, comprising a door formed of a supporting section and a wing section hinged together, a rectilinear guide for the wing section, an actuating lever having one end pivoted to said wing section, a fulcrum lever permanently pivoted at one end and having its free end pivotally attached to 20 the free end of the actuating lever, and a push and pull device connected with said actuating lever at a point between its ends.

2. An operating mechanism for sectional doors, comprising a door formed of a supporting section and a wing section hinged together, a rectilinear guide for the wing section thereof, an actuating lever having one end pivoted to said wing section, a fulcrum lever permanently pivoted at one end and having its free end pivotally attached to the 30 free end of the actuating lever, a push and pull device, a link connecting the push and pull device with said actuating lever, and means for operating the push and pull device.

3. An operating mechanism for sectional doors, comprising a door formed of a supporting section and a wing section hinged together, a rectilinear guide for the wing

section thereof, an actuating lever having 40 one end pivoted to said wing section, a fulcrum lever permanently pivoted at one end and having its free end pivotally attached to the free end of the actuating lever, and a push and pull device directly connected with 45 said operating lever between its ends.

4. An operating mechanism for sectional doors, comprising a door formed of a supporting section and a wing section hinged together, a rectilinear guide for the wing 50 section thereof, a guiding lever having one end pivoted to said wing section, a fulcrum lever permanently pivoted at one end and having its free end pivotally attached to the free end of the actuating lever, a push and 55 pull device provided with a crank arm, and a link connecting said crank arm directly with said operating lever.

5. An operating mechanism for sectional doors, comprising a guide for the wing section thereof, a guiding lever having one end pivoted to said wing section, a fulcrum lever permanently pivoted at one end and having its free end pivotally attached to the free end of the actuating lever, a push and 65 pull device provided with a crank arm, a link connecting said crank arm and said operating lever, and means whereby the crank arm may be moved to a dead center when the link is in a predetermined position.

In witness whereof I have hereunto set my hand, before two subscribing witnesses, this 7th day of March, 1913.

JAMES F. McELROY.
